(57) **CLAIM**

The ornamental design for a LED camera light, as shown and described.

DESCRIPTION

FIG. 1 is a perspective view of a LED camera light showing my new design,

FIG. 2 is a rear perspective view of FIG. 1 thereof;

FIG. 3 is a front view of FIG. 1 thereof;

FIG. 4 is a rear view of FIG. 3 thereof;

FIG. 5 is a left side view of FIG. 3 thereof;

FIG. 6 is a right side view of FIG. 3 thereof;

FIG. 7 is a top view of FIG. 3 thereof; and,

FIG. 8 is a bottom view of FIG. 3 thereof.

The broken lines in the drawings illustrate portions of the LED camera light which form no part of the claimed design.
